UNITED STATES PATENT OFFICE.

FRED R. TAISEY, OF LOWELL, MASSACHUSETTS, ASSIGNOR TO THE LAMSON COMPANY, OF BOSTON, MASSACHUSETTS, A CORPORATION OF NEW JERSEY.

CABLE-CARRIER SYSTEM.

1,157,191.

Specification of Letters Patent. Patented Oct. 19, 1915.

Original application filed July 17, 1913, Serial No. 779,449. Divided and this application filed January 8, 1914. Serial No. 810,979.

To all whom it may concern:

Be it known that I, FRED R. TAISEY, a citizen of the United States, residing at Lowell, in the county of Middlesex and State of Massachusetts, have invented certain new and useful Improvements in Cable-Carrier Systems, of which the following is a specification.

This invention relates to apparatus, disposed at stations of a cable carrier system, for despatching and receiving carriers, and is particularly adapted to what are known as high-line drop stations in systems of this character. Features thereof may also be employed to advantage in low-line systems, and indeed in systems other than those using a cable for the transmission of carriers.

The present application is a division of my application entitled—cable carrier system, Serial No. 779,449, filed July 17, 1913, and relates more particularly to certain features of construction and combinations of elements which were shown by way of exemplification in my said former or parent application but which were not claimed therein.

One of the objects of the present invention is to provide an improved means for elevating a carrier from a station or point disposed at a relatively low level, to a track at a higher level and then to automatically connect the carrier to a propelling cable or otherwise subject it to a propulsive effort, in such manner as to avoid collisions with other carriers *en route* past the station.

Another object of my invention is to provide a carrier-hoisting mechanism which is set into operation by a downward push upon the carrier itself, after the latter has been inserted in said mechanism.

I have further aimed to provide an improved means whereby this hoisting mechanism may be intermittently operated, as needed, by power derived from the cable or like means which propels the carriers along the main track.

Still another object of the invention is to provide an improved means for operatively engaging and disengaging carriers with the propelling means.

These and other objects of my invention will be hereinafter referred to and the novel elements and combination of elements whereby they may be attained will be particularly pointed out in the claims appended 55 hereto.

In the drawings I have exemplified certain preferred forms of the apparatus in question, but I am aware that various other changes and modifications than those shown 60 may be made herein without departing from the spirit of my invention and I hence desire to be limited only by the scope of said claims broadly considered in the light of the specification.

Referring to the drawings: Figure 1 is a front elevation of a high-line drop station. Fig. 2 is a section of the apparatus shown in Fig. 1, taken on line II—II of said figure; the station proper being shown in side elevation. Fig. 3 is a detail section taken on line III—III of Fig. 1. Fig. 4 is a fragmentary rear elevation of the mechanism for tripping free the carrier cable-gripping device and for thereafter causing said device 75 to reengage the cable. Fig. 5 is a front elevation of a modified form of high-line drop station; the carriers on the main track having in this type of apparatus the right of way over carriers being delivered to said 80 main track from the station.

The main track in the present instance comprises an upper or incoming track 1 preferably adapted to support carriers horizontally; both portions of the track being 85 disposed in a horizontal plane in a known manner. The lower, or outgoing track in the apparatus exemplified has the rails 2—2 thereof disposed in the same vertical plane, but I do not wish to be limited in any way 90 to such disposition of the rails where the claims do not clearly specify such arrangement.

The main tracks have been respectively designated forwarding and return tracks 95 with respect to the drop or clerk's station and not with respect to the cashier's station. A track comprising rails 3—3 extends up vertically from a point convenient to the operative and is adapted to deliver carriers 100

to the track the rails of which have been designated 2, and which may hence for brevity conveniently be referred to as track 2, when a switch 4 is in its elevated position, indicated by dot and dash lines at 4' in Fig. 1. A cable 5 serves to propel carriers in the direction indicated by the arrows adjacent thereto, along the respective main tracks; and this cable it will be noted is normally substantially free from kinks or bends where passing a station of the character in question; a feature of considerable importance. An independent drop track 6—6 is adapted to receive carriers from a switch 7 to which selective carriers are delivered in a known manner from the upper or horizontal track 1. The respective track sections and switch are suitably connected together and supported by brackets or connections 8, 9, 10, 11, 12, 13, 14, 15 and 16; the switch 4 being mounted upon a shaft 17 journaled in the bracket 9 and most of the remaining brackets serving further to support operating cams, or the like, in the manner hereinafter described.

The shaft 17 has mounted thereon adjacent its rear extremity an arm 18 which has journaled in its free end a spindle 19 upon the rear extremity of which is keyed a spool 20 and upon the inner end of which is a small pulley 21. This pulley is preferably provided with a roughened surface at the periphery 22 thereof to better adapt it for driving engagement with the cable 5.

Journalled in the lower portion of the bracket 10 is an idler 23 upon which normally the cable 5 lightly rests, but which, when the arm 18 is rotated into its position indicated by dash and dot lines 18', kinks or bends the cable into driving engagement with the pulley 21. At such time obviously the spool 20 will be rotated in the direction of the arrow adjacent thereto and said spool will thereby wind up upon itself a hoisting cord 24. This cord has its lower extremity attached to a pusher 25, which, as indicated in Figs. 1 and 2, rides between the rails 3—3. This pusher may be made of fiber or other suitable material and carries a hook 26, the function of which will be hereinafter referred to. The respective rails 3 are bent out as at 27 to provide an opening through which the guide or retaining lugs 28' of the carrier 28 may be inserted into operative engagement with the pusher 25 as shown in Fig. 1.

The carrier 28 may be of any suitable description adapted to co-act with the rails, but it is preferably of substantially the form shown in Fig. 4; the bottom of the carrier carrying a cable-gripping lug 29 and being slotted as at 30, in a known manner, to permit the projection through said slot of a pivoted cable-gripping member 31.

65 To despatch the carrier it is pushed down-

wardly by the hand of the operative and thereby depresses the pusher 25 to its dotted line position 25', shown in Fig. 1. This causes the hoisting cord 24 to swing the arm 18 downwardly until the pulley 21 is in driving engagement with the cable 5. The bridge 4 is raised at the same time to its dotted line position 4' and these parts are held in such position by a latch 32, pivoted at 33 to an extension of the bracket 9; the operating position of latch 32 being indicated by dotted lines 32' and the latch at such time being in engagement with a shoulder 34 on the bridge 4.

The spool 20 winds up cord 24 in manner aforesaid and the carrier is driven upwardly by the pusher around the bend in track 3 into engagement with track 2. If by chance the pivoted grip member 31 of the carrier is in its closed position, a cam 35 in the path 85 of the ascending carrier will force this member into its open position preparatory for its engagement with the cable 5.

The bridge 4 is slotted at its free end, as at 36 (see Figs. 1 and 3) for the reception alternately of the reduced sections 37—37' of the longer rail 3 and upper rail 2, so that whether the bridge is down or up, it is rigidly held against lateral movement. The rear side of said bridge, as viewed in Fig. 1, carries a knob or button 38 which extends out beyond the cable 5 so that as the bridge is elevated the cable first engages the rounded upper surface of this button and then slips downwardly thereover till it rides over the preferably bluntly pointed extremity 39 and around against the curved under surface 40 of said button, as indicated in Fig. 3. This feature is of great importance since this exceedingly simple device provides means for enabling the ascending carrier to dispose the cable 5 between the jaws of its grip by reason of the fact that the jaw 29 presses upwardly against the cable as the carrier emerges from track 3, which in turn presses the cable upwardly against the cam-acting surface 40, and the shape of the latter is such that the cable is displaced sidewise to clear lug 29; the cable, being under tension, thereafter emplacing itself under said lug, so that when the pivoted grip member 31 encounters the grip-closing cam 41, the carrier is at once operatively engaged with the cable. A spring 42 gives the latch 32 a bias for its operative position, while a spring 43 tends to return the bridge and its associated movable parts to their normal positions, shown in full lines in Fig. 1.

When the carrier has been nearly entered upon track 2, the cam acting upper surface of the hook 26, at the side of the pusher 25, engages a projection 44 upon the latch and swings the latch to its open position releasing the bridge. The bridge cannot drop, however, more than just sufficient to

prevent its becoming re-latched, since the carrier will at such time support its free end and hence until the carrier has been fully entered, by its momentum, upon track 2, said bridge cannot close. The hook 26 also serves to limit the upward travel of the pusher and since at practically the instant after it encounters the latch, the bridge is allowed to close, the tension upon the hoisting cord is relieved and the weight of the pusher returns it to its normal or lower position; cord 24 unwinding from its spool and the parts described being then in position for the despatch of a second carrier.

The means for preventing collisions between carriers en route along main track 2 and carriers being despatched from the clerk's station will now be described. Pivotally connected at 45 to the arm 18 is a bent link 46, the right hand end of which, as viewed in Fig. 1, is connected at 47 to an L-shaped member 48. The latter is pivoted at 49 to the bracket 12 and the distance between the pivotal axes 47 and 49 is substantially equal to the distance between the pivotal axes 45 and 17; so that the straight half of link 46, adjacent member 48, always moves in parallelism with itself and, it may be noted, in parallelism with track 2. Intermediate members 48 and 18 is a second L-shaped part 50 which is pivotally connected to the link 46 at 51 and also pivoted at 52 to bracket 11. The distance between axes 51 and 52 is again made equal to that between axes 47 and 49, and obviously members 48 and 50 rotate together, clockwise or counter-clockwise as the case may be.

The free end 53 of the member 48 is bent over as shown to adapt it for engagement with the pivoted element 31 of the carrier grip, so that when a carrier traveling over track 2 approaches a station from which a carrier is being despatched and the bridge of which station has been raised, its pivoted jaw or grip 31 strikes said end 53 and such carrier is released from the cable to continue on by momentum alone until it strikes the free end 54 of the member 50 which at such time is disposed in its dotted line position. This element positively stops the carrier. It will be observed, too, that the element 54 is also adapted to open the grip of the carrier as well as to stop the latter should the members 48 and 50 chance to have been rotated clockwise to their operative positions after the carrier traversing track 2 has passed member 48 but before it has passed member 50. It may also happen that two carriers are en route over track 2 immediately behind each other in which case both will be disengaged from the cable and brought to rest immediately to the right of the stop 54. Assuming now that one or more carriers are so disposed, the moment that the carrier being despatched from the

station has passed from beneath the bridge 4, the latter closes and thereby the grip-opener 53 and combined grip-opener and stop 54 are lowered while simultaneously the bar or link 46 is raised. The straight portion of the bar, when the bridge is open, lies immediately below the grip elements of the arrested carrier on track 2, so that as it rises its upper edge 46', indicated by dotted lines in Fig. 4, engages the pivoted jaw 31, shown by dotted lines in its lower position in said figure, and presses it upwardly a sufficient distance to enable the jaw to be snapped closed by its spring in the interior of the carrier bottom; although the movement of the cable alone when the pivoted jaw is brought into contact therewith will normally pull this part around the remainder of its travel into apposition with co-acting jaw or grip element 29.

Since the straight portion of the link 46 is relatively quite extended it is adapted to effect the engagement of a plurality of carriers with the cable simultaneously, and hence the one or more arrested carriers immediately resume their travel over track 2 as soon as the carrier leaving track 3 has been entered upon track 2 and its grip thrown into engagement with the cable in manner aforesaid.

Carriers arriving at the clerk's station for which they are intended are automatically removed from the return or incoming track 1 by the engagement of their selective lateral guides (not shown, since these are in common use) with the switch 55, in a known manner; the usual spreader or aperture 56 in the track 1 being provided to enable the carrier guide lugs 28' to free themselves from said track. The usual grip opening cam 55' is provided and the carriers are delivered to track 6 in a known manner, descending this track until they come to rest in the relatively small radius loop 57. The novelty in this preferred receiving track, *per se*, principally resides in the provision of oblique cuts 58, in the respective rails thereof, at substantially the entrance to the loop 57, which permits of the ready withdrawal of lugs 28' of a given carrier therethrough while leaving no opening, such as at 27, through which a carrier may become inadvertently disengaged from said rails.

As the carrier is lifted backward from the loop up toward the cuts 58 its lugs 28' easily enter themselves in these cuts by reason of the natural slight cant given to the carrier by the hand of the operator, while if several carriers have accumulated in this receiving track, the one in the loop grasped by the hand is removed while the others thereabove are lifted slightly so that but one carrier need be removed at a time.

Referring now to the construction shown in Fig. 5. Herein the carrier traversing

track 2 has the right of way over carriers being despatched from the station shown.

The parts not otherwise particularly noted are substantially the same as in the previously described form of device and hence need not again be referred to.

The essential difference between the two constructions resides in the substitution of a lever 60 pivoted at 61 to bracket 10 and having a connection 62 with the latch 32, in place of the link 46 and its associated parts.

The connection at 62 is preferably a slotted one, to permit of free movement between the connected elements, and it operates in the following manner. Assume that a carrier 28 is just being despatched when a carrier on the main track 2 approaches the station, as indicated by the dotted outlined carrier shown to the right on said track, in Fig. 5. The clockwise movement of the latch as bridge 4 is opened swings the inner end of lever 60 downward and its outer end upward as also indicated by dotted lines in said figure. This disposition of the treadle-like free end of lever 60, however, places it in the path of the approaching carrier and if it has not re-descended before this carrier encounters it, it will be positively depressed by the engagement of said approaching carrier therewith, which will rock the lever clockwise and the latch counter-clockwise, releasing the bridge, when spring 43 immediately closes the same, at the same time lifting pulley 21 out of engagement with cable 5, so that the pusher 25 descends prematurely and with it the carrier being despatched, unless the latter has already succeeded in so nearly entering track 2 that its momentum carries it out completely thereinto; in which case its grip will engage cable 5 and both carriers will travel on thereafter one closely behind the other.

The spring 43 may, if desired, be so tensioned that the momentum of the follower 45 or pusher 25 plus that of the carrier being despatched will afford a sufficient pull downwardly upon the hoisting-cord, as they reach substantially their lowermost positions in track 3, to effect a reengagement of the pulley 21 with cable 5 and a re-latching of the bridge in its up-position. In such case the action is as follows: The carrier being despatched has, let us say, reached bracket 13, when the carrier on track 2 trips the latch 55 and the bridge closes, this latter carrier immediately passing thereover. By the time that the through or main line carrier has cleared the bridge, however, the pusher and the carrier supported thereby will have 60 dropped until they have nearly reached the positions in which they are shown in Fig. 1.

Thereafter they will continue to descend under momentum and by gravity until the bridge is again raised and latched and the

pusher again drawn up. This time, if there be no immediately succeeding carrier on track 2 (which seldom happens) the pusher 25 will be pulled up sufficiently to discharge its carrier load onto track 2 in the manner above described.

I desire to call particular attention to the provision of movable means, *e. g.* cams, trips or the like, such as the parts 53, 54 and 46' or 46, for arresting determined carriers under certain conditions and for effecting their reengagement with, or re-subjection to the influence of, the cable or other propelling means.

The provision of means for receiving carriers from the return track which are substantially independent of the power-driven carrier delivering mechanism is of especial value in a system of the character described since it permits of the despatch of carriers from the station by said mechanism without interference therewith by carriers arriving at the station. Finally, it will be noted, that the track or way leading from the station to the forwarding track is of substantially the same gage as said forwarding track, the carrier being successively directly in engagement with and propelled along both of said tracks.

Having thus described my invention what I claim is:

1. In cable carrier apparatus, a track, a cable for propelling carriers along said track, an auxiliary track for directing carriers into engagement with said first mentioned track, a flexible element for propelling carriers along said auxiliary track toward said main track, means for actuating said flexible element by power derived from said cable, means for freeing said flexible element from the action of said cable, and means controlled by a carrier traversing said first mentioned track, for rendering operative said means for freeing said flexible element.

2. In a cable carrier apparatus, a track, a cable for propelling carriers along said track, an auxiliary track for directing carriers into engagement with said first mentioned track, means for propelling carriers along said auxiliary track toward said main track, said means being adapted to be operated by power derived from said cable, means for freeing said propelling means from the action of said cable, and provisions for rendering said last mentioned means operative by the passage of a carrier traversing said main track past a determined point in the latter.

3. In a cable carrier apparatus, a track, a cable for propelling carriers along said track, an auxiliary track for directing carriers into engagement with said first mentioned track, means for propelling carriers

5 along said auxiliary track toward said first mentioned track, and means, controlled by a carrier traversing said first mentioned track, for rendering inoperative said propelling means.

4. In a cable carrier apparatus, a track, a cable for propelling carriers along said track, an auxiliary track for directing carriers into engagement with said first mentioned track, means for propelling carriers along said auxiliary and first mentioned tracks, means for checking the progress of a carrier moving along said auxiliary track, and means, controlled by a carrier traversing said first mentioned track, for actuating said checking means.

5. In cable carrier apparatus, a track, a cable for propelling carriers along said track, means for delivering carriers to said track by power derived from said cable, said carrier delivering means comprising a reciprocable pusher and means for guiding said pusher, and means controlled by a carrier traversing said track for rendering said pusher substantially inoperative.

6. In cable carrier apparatus, a main track, an auxiliary track leading into said main track, a carrier guide adapted to co-act with at least one of said tracks to complete the same and movable in accordance with service requirements in said apparatus into one or the other of two positions, means for holding said guide temporarily in one of said positions, means for releasing said guide when a carrier traveling toward said guide arrives at a determined point in said main track, flexible means for propelling carriers along said tracks, and means for checking the progress of a carrier traversing said auxiliary track under the action of said propelling means, to prevent a collision between said carriers.

7. In cable carrier apparatus a main track, an auxiliary track leading into said main track, a carrier guide adapted to co-act with at least one of said tracks to complete the same and movable in accordance with service requirements in said apparatus into one or the other of two positions, means for holding said guide temporarily in one of said positions, means for releasing said guide when a carrier arrives at a determined point in said main track, flexible means for propelling carriers along said tracks, and operative connections between said guide and said means for checking the progress of a carrier traversing said auxiliary track.

8. In cable carrier apparatus, a track, means for propelling carriers along said track, mechanism for delivering carriers to said track, said mechanism including a hoisting cord and provisions whereby a downward pull upon said cord starts said mechanism into operation, and means controlled

65 by a carrier traversing said track for rendering said mechanism inoperative whereby to prevent a collision between a carrier being delivered by said mechanism to said track and said carrier traversing said track.

9. In cable carrier apparatus, a main track, 70 an auxiliary track adapted to deliver carriers thereto from a station, means for propelling carriers along said track, means for positively propelling carriers along said auxiliary track, and means for preventing a collision between a carrier traversing said main track past said station and a carrier being propelled from said station to said main track, said last mentioned means including provisions for checking the progress of carriers being propelled along said auxiliary track.

10. In cable carrier apparatus, a main track, guiding means adapted to deliver carriers thereto from a station, means for successively positively propelling carriers along a portion at least of said guiding means and main track, and means for preventing a collision between a carrier traversing said main track and a carrier being despatched from 90 said station, said last mentioned means including provisions for arresting the progress of said carrier on said guiding means.

11. In cable carrier apparatus a main track, an auxiliary track adapted to deliver 95 carriers thereto, means for propelling carriers along said main track, mechanism for propelling carriers along auxiliary track, said mechanism comprising a support for a carrier to be despatched from said 100 station and driving connections including a latch closed by a push upon said support, for starting said mechanism into operation, and a lever movable by a carrier traversing said main track to render said mechanism inoperative.

12. In cable carrier apparatus, a main track, an auxiliary track adapted to deliver carriers thereto from a station, means for propelling carriers along said main track, 110 mechanism, driven by power derived from said carrier propelling means, for propelling carriers along said auxiliary track, said mechanism comprising a support for a carrier to be despatched from said station and driving connections, including a latch closed by a push upon said support bar starting 115 said mechanism into operation, and means controlled by a carrier traversing said main track past said station, for releasing said 120 mechanism from the action of said carrier propelling means.

13. In carrier despatch apparatus, a main way, an auxiliary way leading thereinto means for propelling carriers along said 125 auxiliary way, separate means for propelling carriers along said main way, mechanism for temporarily operatively connect-

ing said two means whereby to drive one from the other for a limited period of time, and means controlled by a carrier traversing said main way for disconnecting said two means.

14. In cable carrier apparatus, a main way, a second way disposed at an angle to said main way and leading thereinto, means for propelling a carrier in actual contact with said second way, a cable for propelling said carrier along said main way, mechanism for temporarily operatively connecting said means and cable whereby to drive one from the other for a limited period of time, and means, controlled by a carrier traversing said main way, for disconnecting said means and mechanism.

15. In cable carrier apparatus, a main track, a continuously driven cable for propelling carriers therealong, a fixed auxiliary track of substantially the same gage leading into said main track, a switch, discontinuously operated means, connected with said switch and driven from said cable when operative, for propelling carriers along said auxiliary track into said main track, and means for rendering said last mentioned means substantially inoperative when a carrier traversing said main track would be subject to a collision with said switch.

16. In cable carrier apparatus, a track, a carrier adapted to travel along said track, a cable for propelling said carrier along said track, a station, means for delivering said carrier from said station to said track, said means including an element adapted to have motion imparted thereto by said cable, means for engaging said cable and element to thereby move the latter, means for normally interrupting said engagement after said carrier has been despatched from said station, and means for interrupting said engagement before said carrier has been delivered to said track when a carrier traversing said main track would be subject to a collision as the result of the despatch of said carrier from said station.

17. In cable carrier apparatus, a track, a cable for propelling carriers along said track, a station, means for delivering carriers from said station to said track, said means including a revoluble element adapted to be driven by said cable, means for engaging said cable and element to thereby drive the latter, means for thereafter interrupting said engagement after the lapse of a substantially determined interval of time, and collision preventing means for effecting said disengagement before the end of said period of time, when a carrier traversing said track past said station would be subject to a collision as the result of the despatch of said carrier from said station.

18. In the cable carrier apparatus, a main track, means, including an auxiliary track,

for guiding carriers from a station at a lower level than said main track onto the latter, power means, including a cable, for positively propelling carriers along both said main and auxiliary tracks, and means, controlled by a carrier *en route* along said main track, for checking the progress of a carrier traversing said auxiliary track.

19. In a cable carrier apparatus, a main track, means, including an auxiliary track, for guiding carriers up from a drop-station to said main track, said main track having a gap therein where said guiding means deliver carriers thereto, a movable part of said guiding means being adapted to bridge said gap, power means, including a cable, for positively propelling carriers along both said main and auxiliary tracks, and means controlled by a carrier *en route* along said main track for closing said bridge, when the latter is open, as said last mentioned carrier reaches a determined point in said main track.

20. Cable carrier apparatus comprising, a main track, means, including a fixed auxiliary track, for guiding carriers from a station at a lower level than said main track onto the latter, power means including a cable, for positively propelling carriers along both said main and auxiliary tracks, and means, controlled by a carrier *en route* along said main track, for preventing the movement of a carrier, being despatched from said station, past a determined point in said guiding means.

21. Carrier despatch apparatus comprising a main track, an auxiliary track to deliver carriers thereto, a carrier adapted for direct operative engagement successively with said tracks, power driven means for positively propelling said carrier successively along said tracks, and means for stopping the forward movement of a carrier on said auxiliary track whenever normal service conditions in said main track fail to permit of an unimpeded delivery of said carrier thereto.

22. A cable carrier apparatus comprising a way, a portion at least of which is set at an angle extending downwardly from a horizontal plane, mechanism for propelling a carrier upwardly along said portion of said way, and means to start said mechanism into operation by a downward movement of said carrier under the action of gravity.

23. In cable carrier apparatus, a track, a cable, means adapted to be driven by said cable to move said carrier along said track, means for stopping said carrier while *en route* along said track and permitting it to move substantially free from the action of said cable driven means, and means for thereafter automatically re-subjecting said carrier to said action by a downward movement thereof under the action of gravity.

24. In cable carrier apparatus, a track, a cable, means to transmit power from said cable to said carrier to raise the latter to said track, means to subject said carrier to said 5 action by a downward movement thereof under the action of gravity, and means to guide said carrier in said downward movement.

25. A cable carrier despatch apparatus 10 comprising a way, cable driven means for

propelling carriers along said way, a carrier to travel on said way, and automatic means for causing a reversal of the direction of travel of said carrier along said way.

In testimony whereof I have affixed my ¹⁵ signature, in the presence of two witnesses.
